P. H. MACK

PRESSURE RELIEF PACKER

Filed Jan. 29, 1924

INVENTOR

UNITED STATES PATENT OFFICE.

PATRICK H. MACK, OF BRADFORD, PENNSYLVANIA, ASSIGNOR TO OIL WELL SUPPLY COMPANY, OF PITTSBURGH, PENNSYLVANIA, A CORPORATION OF PENNSYLVANIA.

PRESSURE-RELIEF PACKER.

Application filed January 29, 1924. Serial No. 689,307.

To all whom it may concern:

Be it known that I, PATRICK H. MACK, a citizen of the United States, residing at Bradford, in the county of McKean and State of Pennsylvania, have invented certain new and useful Improvements in Pressure-Relief Packers, of which the following is a specification.

This invention is for a packer for oil wells, 10 and relates particularly to a packer having means associated therewith for controlling the gas pressure in the well.

It is a common practice in the oil fields to insert a packer in the well at a proper elevation to prevent water from the upper strata of earth from flowing down into the hole. Such packers must often be inserted against the pressure of a rising flow of oil and gas. Furthermore, once the packer has 20 been set in the well, gas will frequently accumulate below the packer, and, where the well is being pumped, this pressure, up to a certain point, may increase the efficiency of the pump, but beyond a certain limit, 25 will interfere with the proper valve actuation.

After the packer has been set, it is sometimes desirable to remove it, either to be reset in the same well or to be used in another well. Removal of the packer is facilitated if the body of fluid collecting above it may be drained before the removal is attempted.

According to the present invention, I provide a packer having a slidable sleeve valve which may be opened and closed to control the escape of gas from the well and control the drainage of accumulated fluid above the packer into the well. The construction is such that the packing element may be set by manipulation of the tubing to retain it in an expanded position, even when the weight of the string of pipe is removed therefrom to open the valve.

Another important object of the invention is the provision of a valve which may be set in open position until manually released to close it.

Another object of the invention is to provide a valve packer which may be removed from the hole any time it may be necessary to do so.

The invention may be readily understood

by reference to the accompanying drawings, in which:

Fig. 1 is a longitudinal section through the packer, showing the parts in position to be lowered into a well;

Fig. 2 is a similar view indicating the position of the parts after the packer is set and with the valve closed;

Fig. 3 is a cross section on line III—III of Fig. 1;

Fig. 4 is an enlarged detail view of a shearing pin connection between the reciprocal valve and the packer head.

Fig. 5 is a detail view.

In the drawings, 5 designates a tubular packer body having a shoe 6 threaded onto its lower end and having a head 7 screwed onto its upper end. A shear pin 7' may be used to non-rotatably hold head 7 on the body.

Surrounding the body 5 below head 7 is a collar 8, an anti-friction bearing 9 being interposed between the head and collar. The lower surface of the collar has a downwardly extending flange that embraces the contracted top of a rubber packer 10, whose upper end bears against said under face of the collar.

The lower end of the rubber packing member abuts against the sliding wedge 11 for expanding slip 12 carried by sliding cage 13. Bowed leaf springs 14 are provided with one end secured to the cage and one end bearing on the shank of a slip.

In the body is a vertical slot 15 having a lateral offset 15^a at the bottom thereof. The cage has a pin 16 for engagement in this slot. The top of head 7 has an inwardly sloping beveled valve seat 17 thereon and an outwardly beveled surface 18.

Slidable within the tubular head is a sleeve 19 having a threaded upper end and a lower end portion 19^a of slightly increased diameter. This shouldered end portion 19^a cooperates with the inside of the tubular head, as shown in Fig. 1, to limit the relative movement of the sleeve in the head, as will be hereinafter more fully described.

Above the enlarged part 19^a are vertical slots 24 having lateral offsets 24^a, said offsets being similar to the one in slot 15, but having a slight downward inclination away from the vertical part of the slot, as shown

in Fig. 5. Passing through the head 7 are pins or bolts 25 whose inner ends engage in the slots 24.

In addition to the slots, the sleeve has a plurality of holes or openings 26 therein. Additional openings 27 at the level of the valve seat 17 are provided to provide drainage for the valve seat.

Screwed onto the threaded upper end of the sleeve 19 is a connecting member or valve head 28 having a beveled lower end 29 for cooperation with seat 17. This connector is interiorly threaded at 30 to receive the lower well tubing 31 and is threaded at 32 to receive the upper or letting-in tubing 33.

In operation, the parts are in the position shown in Fig. 1. After a sufficient length of tubing 31 has been secured to the packer, the packer is lowered into the well by tubing 33 screwed into threads 32 until it is at the desired depth. The letting-in tubing 33 is then turned slightly to the right. This motion will first tend to move pins 25 out of the lateral parts 24^a of slots 24. Upon further turning in the same direction, the rotary motion is transmitted to body 5.

By reason of their frictional resistance with the sides of the hole, springs 14 will hold the cage 13 from turning, so that a relative movement will be effected, bringing pin 16 out of the horizontal offset 15^a of slot 15 into line with the vertical part of the slot. Then, by lowering pipe 33, springs 14 holding the cage against vertical movement, the packer is lowered, forcing slips 12 out into binding engagement with the wall of the hole. At the same time, the weight of the packer and the superimposed column of pipe 33 will tend to urge tube 5 down relatively to the cage, the tube sliding also with relation to wedge 11. The rubber packer 10 is thus compressed between the downwardly moving upper part of the packer and the wedge, and caused to expand.

After the packer has been set, tube 33 may be lowered to seat valve 29 on seat 17 to close the gas by-pass.

Should it be desired to apply pressure to the packing 10, so as to insure that it will remain set even when the weight of the pipe is removed therefrom, as when the valve is open, tube 33 may be rotated to the right, shearing pin 7 and screwing head 7 down on the threaded upper end of body 5. This will force ring 8 down, and compress the packing from the top. The anti-friction slip ring or bearing 9 is provided to facilitate the rotation of head 7 with respect to collar 8. Rotation in the opposite direction will serve to turn head 7 in a direction to relieve the pressure on the packer, as when the packer is to be pulled.

As the packers are often lowered into a well against very high pressures, it is desirable that the gas escape ports be kept

open, at least until the packer is set. This is insured in the present construction by reason of the fact that a relative reciprocating movement cannot be effected between the packer body and the sleeve until pins 25 are in the vertical parts of slots 24, and this may not occur until a relative rotary movement has been effected between them. Due to the weight of the packer and to the shape of the lateral offsets 24^a, this is not liable to accidentally occur. Therefore, there is little likelihood of the valve closing prematurely by reason of the packer becoming hung in the well or by reason of the resistance to the downward movement of the packer by the pressure in the well.

Due to the enlargement 19^a at the end of sleeve 19, the weight of the suspended packer, which might otherwise hang on pins 25, may be distributed to be partially or wholly carried by the shoulder at 19^a. This shoulder also forms a safety factor in that it prevents the loss of parts in the event of the pins 25 being sheared.

A packer constructed in accordance with my invention is simple in construction, and positive in operation. The particular form of packer apart from the valve mechanism is known to the art as a hook-wall packer. In my application for patent filed Jan. 29, 1924, Serial No. 689,305, I have illustrated a control head attachment adapted to accomplish the same purpose as the present invention.

I claim as my invention:

1. A packer comprising a body, a packing member on the body, means movable longitudinally of the body for expanding the packing member, a reciprocable valve for opening or closing the end of the packer, and other means movable longitudinally of the body operable through said valve for expanding the packing member.

2. A packer comprising a body, a valve member for closing one end of the body, a sleeve slideable in the body connecting the valve and the body, said sleeve having vertical slots therein, and means on the body engaging in the slots.

3. A packer comprising a body, a valve member for closing one end of the body, a perforated sleeve carried by the valve member slideable in the body, and means on the body having a slideable non-rotatable engagement with said sleeve for connecting the body and sleeve.

4. A packer comprising a body, a valve member for closing one end of the body, a sleeve carried by the valve member slideable in the body, said sleeve having a vertical slot therein, said slot having a lateral offset at one end thereof, and means carried by the body engaging in said slot.

5. A packer comprising a body, packing means on the body, means on the lower end

of the body for expanding the packing member, a head screwed onto the upper end of said body, said head being arranged when turned in one direction to expand the packing member, a valve member, a sleeve carried by the valve member slidably entered in said head, said sleeve having a vertical slot therein, and a pin in said head projecting into the slot whereby said sleeve may reciprocate with respect to the head and transmit rotary motion thereto to compress or relieve the packing member.

6. A packer comprising a body, a packing means on the body, reciprocable means for expanding the packing means, rotatable means for expanding the packing means, and a reciprocable valve mechanism connected with the rotatable packing expanding means.

7. A packer comprising a hollow body, a packing on the body, a valve member for opening and closing one end of the body, means at each end of the body movable relatively to the other; and to the body for expanding the packing, said means at one end of the body being operatively connected with said valve, and means on the valve member through which said valve member may be connected with a well tubing.

8. A packer comprising a hollow body, a packing element on the body, a reciprocable valve at one end of the body for opening and closing communication therethrough, means at one end of the packing element adapted to be actuated by the weight of the well tubing to expand the packer, rotatable means operatively connected with said valve at the other end of the packing element movable by rotation into a position to hold the packer expanded, said valve being reciprocable relatively to the said rotatable means but substantially non-rotatable with respect thereto, and a well tubing connected with the valve.

9. The combination with a hook-wall packer having a cage and slips on the lower end thereof and having a vertical slot with a lateral offset in which a pin on the cage engages, of a head on the packer having a sleeve slidably therein, said sleeve also having a vertical slot therein with a lateral offset, of a pin in the head engaging in the slot in the sleeve, and a member at the top of the sleeve to which well tubing may be attached.

10. The combination with a hook-wall packer having a cage and slips on the lower end thereof and having a vertical slot with a lateral offset in which a pin on the cage engages, of a head on the packer having a sleeve slidably therein, said sleeve also having a vertical slot therein with a lateral offset, of a pin in the head engaging in the slot in the sleeve, a member at the top of the sleeve to which well tubing may be at-

tached, and a shearing pin for temporarily connecting the sleeve and head whereby the cage and slips may be operated before effecting relative movement between the head and sleeve.

11. The combination with a hook-wall packer having a packing element thereon and means at the lower end thereof for expanding said element, of a head threaded onto the upper end of the packer for expanding the packing element when screwed down on the packer, a perforated sleeve fitted into the head, said sleeve being reciprocable with respect to the head but having a limited rotatable movement with respect thereto, and a valve member at the top of the sleeve to which well tubing may be attached, said head having a seat for co-operation with the valve member.

12. The combination with a hook-wall packer having a packing element thereon and means at the lower end thereof for expanding said element, of a head threaded onto the upper end of the packer for expanding the packing element when screwed down on the packer, a sleeve slidably fitted into the head, said sleeve having a vertical slot therein, a pin in the head projecting into the slot, whereby the sleeve may reciprocate relatively to the head, but is substantially non-rotatable with respect thereto, a valve at the upper end of the sleeve adapted to seat against said head, and means on the valve to which tubing may be attached.

13. The combination with a hook-wall packer having a packing element thereon and means at the lower end thereof for expanding said element, of a head threaded onto the upper end of the packer for expanding the packing element when screwed down on the packer, a sleeve slidably fitted into the head, said sleeve having a vertical slot therein in the bottom end of which is a lateral offset, a pin in the head engaging in the slot, whereby the sleeve and head are substantially non-rotatable with respect to each other except for the length of said lateral offset when the pin and lateral offset are in the same horizontal plane, a valve at the upper end of the sleeve adapted to seat against said head, and means on the valve to which tubing may be attached, said pin when in said offset serving to prevent reciprocable movement between the sleeve and the head.

14. The combination with a packer, of a head having a valve seat thereon at the top of the packer, a valve member for cooperation with the seat having a perforated sleeve secured thereto, means for slidably connecting the sleeve and head, means on the valve within the diameter of the sleeve for receiving a tubing, a tubing screwed into the top of the valve, said valve and sleeve serv-

ing to suspend the packer from the tubing, and a tubing screwed into the top of the valve inside the sleeve.

15. The combination with a hook-wall packer, of a gas control attachment having a vertically reciprocable valve associated therewith, and a pin and slot connection between relatively movable parts of the valve for preventing a closing movement of 10 the valve except when such parts are in a predetermined position.

16. The combination with a hook-wall packer, of a gas control attachment having

a vertically movable valve member associated therewith, and a pin and slot connection between a part of the valve and a part of the packer including a longitudinally and transversely slotted member forming one part of the attachment and a pin engaging in the slot carried by a part relatively movable with respect to the slotted member, said pin when engaged in the transverse part of the slot preventing the closing of the valve.
